CLAIM

We claim the ornamental design for a cover portion for a dispenser, as shown and described.

DESCRIPTION

FIG. 1 is a perspective view of a cover portion for a dispenser, showing our new design.

FIG. 2 is a top view thereof.

FIG. 3 is a front view thereof.

FIG. 4 is a back view thereof.

FIG. 5 is a right side view thereof; and,

FIG. 6 is a left side view thereof.

The broken line showing of the dispenser is for illustrative purposes only and forms no part of the claimed design.
